UNITED STATES PATENT OFFICE

2,461,527

PERCUSSIVE TOOL

John C. Curtis and Elmer G. Gartin, Claremont,
N. H., assignors to Joy Manufacturing Company,
a corporation of Pennsylvania

Application February 13, 1943, Serial No. 475,782

9 Claims. (Cl. 121—7)

1

This invention relates to percussive tools and more particularly to improvements in rock drills of the reciprocating piston, hammer type.

An object of the present invention is to provide an improved percussive tool. Another object is to provide an improved hammer rock drill having an improved pressure fluid motor for percussively actuating the drill steel. A further object is to provide an improved pressure fluid motor having a novel fluid distribution means. Yet another object is to provide an improved rotation mechanism for the drill steel of a hammer rock drill. Yet a further object is to provide improved fluid cushioning means for the hammer piston of the motor of a hammer rock drill. A still further object is to provide an improved chuck structure for a hammer rock drill. Still another object is to provide an improved hammer motor having improved means for transmitting the hammer blows to the shank of the drill steel. A further object is to provide an improved rock drill of an extremely compact design. Still another object is to provide an improved hammer piston structure for a hammer rock drill. Other objects and advantages of the invention will, however, hereinafter more fully appear.

In the accompanying drawings there are shown for purposes of illustration several forms and modifications which the invention may assume in practice.

In these drawings:

Fig. 1 is a somewhat diagrammatic view in central longitudinal vertical section through a rock drill constructed in accordance with a preferred illustrative embodiment of the invention.

Fig. 2 is a sectional view similar to Fig. 1, showing the hammer piston and fluid distributing valves in a different position.

Fig. 3 is a cross sectional view taken on line 3—3 of Fig. 1.

Fig. 4 is a cross sectional view taken on line 4—4 of Fig. 1.

Fig. 5 is a side elevational view of the improved hammer piston.

Fig. 6 is an end elevational view of the hammer piston shown in Fig. 5.

Fig. 7 is a perspective view of the chuck bushing.

Fig. 8 is a perspective view of the piston striking button.

Fig. 9 is a cross sectional view taken on line 9—9 of Fig. 1.

Fig. 10 is a cross sectional view taken on line 10—10 of Fig. 11.

Fig. 11 is a fragmentary longitudinal sectional

2

view showing a modified form of the construction.

Fig. 12 is a fragmentary longitudinal sectional view showing a further modified construction.

Fig. 13 is a detail sectional view taken on line 13—13 of Fig. 12.

Fig. 14 is a fragmentary sectional view, similar to Fig. 1, showing another embodiment of the invention.

Fig. 15 is a sectional view, similar to Fig. 14, showing the hammer piston in a different position.

Fig. 16 is a cross sectional view taken on line 16—16 of Fig. 14.

Fig. 17 is a detail sectional view taken on the line 17—17 of Fig. 14.

In the illustrative embodiment of the invention shown in Figs. 1 to 9 inclusive, the rock drill includes a motor cylinder 1 having a bore 2 containing a reciprocating hammer piston 3. Attached by conventional side rods 4, 4 extending longitudinally along the opposite sides of the cylinder, to the opposite ends of the cylinder, is a relatively short front chuck housing 5 and a rear head block 6. The hammer piston is of substantially the same external diameter throughout its length and has a rear piston head 7 slidably fitting the cylinder bore. The piston head periphery is annularly grooved at 8. Formed on the piston exterior in advance of the piston head are longitudinal flutes or grooves 9 which are slidably interlocked with straight keys 10 formed in a sleeve-like chuck nut 11. The piston flutes 9 extend longitudinally on the exterior periphery of the hammer piston intermediate the extreme end pressure areas of the piston, and extend in advance of the impact surface on the piston which strikes against the shank 12 of a conventional collared drill steel 13, as will later be explained in detail.

The chuck nut has a tight press fit with a bore 14 in a chuck sleeve 15 rotatably mounted in an enlarged bore 16 in the forward portion of the motor cylinder and in aligned stepped bores 17 and 18 in the chuck housing 5. A key pin 19 serves to hold the chuck nut against rotation in the chuck sleeve bore. A replaceable hardened steel sleeve or bushing 20 has a press fit within the chuck sleeve bore 14 and provides a guide for the hammer piston when the latter is in its forward position, with the outer surfaces of the projections between the piston flutes slidably engaging the sleeve interior. The outer surfaces of the projections between the flutes lie in a circle of the same diameter as the piston head,

and these surfaces enter the cylinder bore as the piston moves rearwardly. The chuck sleeve has a reduced front bore 21 which receives the reduced front end portion 22 of the piston when the latter approaches its foremost limit of travel. The front end portion 22 on the piston enters the bore 21 as the piston nears the end of its forward stroke, thereby trapping the fluid therein and providing a fluid cushion for the piston. Pressed tightly in a bore 23 in the forward portion of the chuck sleeve 15 is a replaceable chuck bushing 24 held against rotation by a key pin 25. This chuck bushing has a socket 26 of hexagonal cross section extending centrally completely therethrough for receiving the hexagonal shank of the drill steel. The front wall 27 of the chuck housing has a bore 28 which receives a front portion of the chuck bushing as shown. The chuck bushing is recessed at 29 to receive the steel collar 30 and the chuck housing has a central opening 31 in its front wall through which the drill steel extends.

As illustrated, the hammer piston 3 has a central bore or recess 32 opening through its front end surface and the chuck bushing is received in this bore when the piston approaches its foremost position. Pressed tightly in the piston bore and engaging a shoulder 33 at the rear end of the piston bore 32 is a replaceable cylindric striking button 34 of hardened steel, and the forward surface of this striking button is adapted to strike against the steel shank as the hammer piston reciprocates.

The motor cylinder has an enlarged rearward bore 35 aligned with the cylinder bore at the rear end of the latter and having arranged therein a rear head plate 36 abutting a shoulder 37 at the front end of the bore. The rear head plate 36 has a reduced sleeve-like projection 38 which extends forwardly into the cylinder bore and the rear head of the piston is recessed at 39 to receive the projection 38 as the piston approaches its rearmost position. Also arranged in the bore 35 is a ratchet ring 40 and to the rear of the ratchet ring is a valve box cover 41, a valve box 42 and a cylindric rear plate 43. The parts 36, 40, 41, 42 and 43 are held in position within the bore 35 by clamping engagement of the rear head block 6 with the plate 43 and a suitable dowel pin 44 serves to hold the parts 36, 40, 41, 42 and 43 against rotation with respect to the cylinder. The valve box, the cover and the cylindric plate 43 cooperate to provide a valve chamber 45 which receives a pair of cooperating fluid actuated, fluid distributing valves 46 and 47 which are adapted to control the supply of fluid under pressure to the motor cylinder. This valve mechanism may be similar to that described in the patent to John C. Curtis, No. 2,224,861, dated December 17, 1940. Fluid supply passages 48 in the parts 36, 40 and 41 connect the front end of the valve chamber with the rear end of the cylinder bore, while the rear end of the valve chamber is connected by supply passages 49 to the front end of the cylinder bore just rearwardly of the chuck nut and chuck sleeve as shown. Fluid under pressure may be conducted from the front end of the cylinder bore through passages 50 which extend longitudinally between certain of the piston flutes to the bore 21 in advance of the piston. Communicating with the cylinder bore at longitudinally spaced points at opposite sides of a centrally located cylinder exhaust groove 51, are throwing passages 52 and 53 which in turn com-

municate with annular chambers 54 and 55 respectively at the inner sides of annular flanges 56 and 57 on the valves respectively. The cylinder exhaust groove 51 is connected to atmosphere through an exhaust port 58. The rear head block has a transverse bore 59 which receives a rotary throttle valve 60 having a central supply chamber 61 connected to a source of pressure fluid supply. A port 62 in the valve connects the chamber 61 with a passage 63 communicating with the valve chamber 45 within the valves.

Arranged within the ratchet ring 40 and journaled in bores in the rear head 36 and valve box cover 41 is a pawl carrier 64 carrying spring-pressed pawls 65 engageable with the internal teeth 66 of the ratchet ring. This pawl carrier has internal spiral ribs 67 which are slidingly engaged in spiral grooves 68 on a rifle bar 69. Because of the relatively great length of the spiral ribs within the pawl carrier there are provided relatively large wear surfaces. The rifle bar has an annular enlargement 70 at its forward end secured within the piston by a nut 71 threaded within the piston bore. The nut 71 has teeth interlocked with the spiral grooves of the rifle bar 69 for locking the latter against rotation with respect to the piston. The valve box cover 41 has a rearwardly projecting cylindric portion 72 closed at its rear end and providing a recess 73 for receiving the rear end of the rifle bar 69 when the piston is in its rearward position. This cylindric portion 72 has a tight fit at 74 with the walls of a bore in the plate 43 to prevent fluid leakage. The ratchet and pawl mechanism causes the hammer piston to be rotated during its return stroke and the rotary motion of the hammer piston is transmitted through the flutes on the piston periphery and the chuck nut to the chuck sleeve 15 and thence through the chuck bushing 24 to the drill steel shank. It is accordingly evident that the drill steel is intermittently rotated during the reciprocating movement of the hammer piston. A gland plug 75 is threadedly connected at 76 within the rear head block and serves to secure a cleansing fluid conducting tube 77 in operative position. This fluid conducting tube extends centrally through bores in the rifle bar and striking button into the bore of the drill steel. Fluid under pressure may be supplied through the gland plug to the fluid conducting tube through a port 78 in the valve communicable with a passage 79 leading through the gland plug to the tube interior.

In the modified constructions shown in Figs. 10, 11, 12 and 13, instead of the rifle bar secured to the hammer piston, a conventional type of ratchet and pawl mechanism is shown. In this instance, a pawl carrier 80 has an integral forwardly projecting rifle bar 81 engaging a rifle nut 82 threadedly secured within the hammer piston. A striking button 83 is secured with the hammer piston and has reduced front and rear portions 84 and 85, the latter having a press fit in a reduced bore 86 in the piston. The front reduced portion 84 has a front striking surface and is adapted to deliver the piston blows to the drill steel shank. The cooperating fluid distributing valves 87 and 88, in this modified construction, are arranged in a valve chamber 89 which encircles the ratchet ring 90. By this novel arrangement extreme compactness is obtained as well as greater simplicity. Otherwise these modified constructions are similar to that above described.

The general mode of operation of the improved

rock drill above described will now be given. When the parts are in the position shown in Fig. 1, fluid under pressure may flow from the interior of the throttle valve 60 through port 62 and passage 63 to the valve chamber 45. Fluid may flow from the valve chamber past the rear face of the rear valve 46 and through supply passages 49 to the front end of the cylinder bore 2 in advance of the piston head 7 and also through passages 50, 50 between the keys of the chuck nut 11 to the chuck sleeve bore 21 in advance of the front end of the hammer piston. Pressure fluid acts on the effective front pressure area of the piston to move the latter rearwardly to effect its return stroke. As the hammer piston moves rearwardly the piston head face first overruns the exhaust groove 51 and thereafter the groove 8 on the piston head connects the throwing passage 52 to the exhaust groove. Upon continued rearward piston movement the rear edge of the piston head overruns the throwing passage 52 so that pressure fluid may flow from the forward end of the cylinder bore through the throwing passage 52 to the bore 54 to act on the front face of the annular flange 56 of the rear valve 46 to throw the latter rearwardly from the position shown in Fig. 1 to the closed position shown in Fig. 2. Thereafter the groove 8 in the piston head connects the throwing passage 53 to the exhaust groove 51 and upon continued rearward piston movement the piston head overruns the exhaust groove 51 connecting the front end of the cylinder bore to exhaust. As the hammer piston approaches the rearward end of its travel the pressure fluid trapped in the rear end of the cylinder bore is compressed and the compression pressure acts through the passages 48 on the forward face of the flange 57 of the front valve 47 to throw the latter rearwardly from the position shown in Fig. 1 to the position shown in Fig. 2. As the projection 38 on the rear cylinder head 36 enters the recess 39 in the piston, a pressure is built up to provide a cushion which prevents the piston from striking against the rear cylinder head. When the parts are in the position shown in Fig. 2 pressure fluid may flow from the valve chamber 45 past the front face of the front valve 47 and through supply passages 48 to the rear end of the cylinder bore, the pressure fluid acting on the rear pressure area on the piston to move the latter forwardly to effect its working stroke. As the piston moves forwardly the piston head first covers the exhaust groove and thereafter the groove 8 on the piston head connects the throwing passage 53 with the exhaust groove. Upon continued forward piston movement the rear edge of the piston head overruns the throwing passage 53 so that fluid under pressure is admitted from the rear end of the cylinder bore through the passage 53 to the bore 55 at the rear side of the valve flange, the pressure fluid acting on the rear face of the valve flange to throw the front valve 47 forwardly to its closed position shown in Fig. 1. Upon continued forward piston movement the groove 8 on the piston head connects the throwing passage 52 with the exhaust groove 51 and thereafter the piston head overruns the exhaust groove connecting the rear end of the cylinder bore to exhaust. As the hammer piston approaches the end of its forward travel, a compression pressure is built up within the chuck sleeve at the forward side of the piston, and this compression pressure is transmitted through the passages 50 and supply passages 49 to the valve chamber at the rear side 75

of the valve flange 56, the pressure fluid acting on the rear pressure area of the valve flange to throw the rear valve 46 forwardly to the position shown in Fig. 1. When the hammer piston reaches the position shown in Fig. 1 the front face of the striking button 34 engages the drill steel shank to transmit the blow of the hammer piston to the drill steel to drive the latter forwardly. As the hammer piston nears its forward end of travel the reduced portion 22 on the piston will enter the bore 21, if the striking button's engagement with the end of the steel shank does not prevent, so that a cushion is provided to prevent the piston from striking against the chuck sleeve. The events above described are rapidly repeated during normal operation of the motor.

During the forward piston stroke the rifle bar 69 effects rotation of the pawl carrier 64 causing the pawls 65 of the pawl carrier to slip over the teeth 66 of the ratchet ring so that the forward piston movement is free and unimpeded, thereby to enable the piston to strike a powerful blow against the drill steel shank. During the return stroke of the hammer piston the pawls 65 of the pawl carrier engage the ratchet teeth 66 of the ratchet ring to hold the pawl carrier against rotation, thereby causing the rifle bar 69 to impart a rotary motion to the hammer piston which is transmitted through the chuck nut, chuck sleeve and chuck bushing to the drill steel. When it is desired to admit fluid under pressure through the fluid conducting tube 77 to the drill steel bore to clean out the drill hole, the throttle valve 60 may be rotated into a position to bring the port 78 into communication with the passage 79 which is connected through the gland plug 75 to the tube bore.

In the embodiment of the invention shown in Figs. 14 to 17 inclusive the cylinder and piston structure and the associated fluid distribution means together with the rotation mechanism for the drill steel are similar to those above described. In this instance, the shank of the drill steel 95 is supported in a chuck bushing 96 threadedly secured at 97 within the bore of a chuck sleeve 98. The chuck sleeve is rotatably mounted in the bore of an elongated chuck housing 99 attached to the front end of a motor cylinder 100. Formed on the chuck bushing is a flange 101 overlying the front end of the chuck housing to prevent access of dirt to the bearing surfaces. The motor cylinder has a bore 103 containing a reciprocable hammer piston 104, the latter being similar to that shown in Fig. 11. The fluid distributing valve mechanism and the ports and passages controlled thereby are similar to those in Fig. 1. As in the modified constructions shown in Figs. 11 and 12, described above, the rifle bar 81 of the drill steel rotation mechanism engages a rifle nut 82 secured within the hammer piston. Journaled in bores in the motor cylinder 100 and chuck housing 99 is a rotation sleeve 105 having longitudinal keys 106 engaged in the longitudinal flutes 9 on the hammer piston. Also engaged with the keys 106 on the rotation sleeve 105 are flutes 107 formed on the chuck sleeve 98. The chuck sleeve has an annular flange 108 arranged between the front end of the rotation sleeve 105 and a shoulder 109 in the chuck housing, and the chuck sleeve has a rearwardly projecting reduced portion 110 receivable in the bore 32 in the hammer piston. Mounted in the bore of the reduced portion 110 is a tappet 111 having a striking portion 112 engageable with the drill steel

shank. As the hammer piston reciprocates, the striking button 34 in the piston hammers against the tappet 111 and the latter transmits the piston blows to the drill steel shank. As in the embodiment above described, as the hammer piston moves rearwardly, it is rotated through the rifle bar and ratchet and pawl mechanism, and the rotary motion of the piston is transmitted through the rotation sleeve 105, chuck sleeve 98 and chuck bushing 96 to the drill steel. As the hammer piston moves forwardly to effect its working stroke, the pawls of the ratchet mechanism slip over the ratchet teeth so that the hammer piston moves freely to deliver a blow to the shank of the drill steel. Otherwise, this embodiment of the invention is similar to that above described. Since this embodiment of the invention operates in a manner similar to the preferred embodiment, further description of the mode of operation thereof is unnecessary.

As a result of this invention, it will be noted that an improved rock drill is provided which is extremely longitudinally compact while a relatively long piston stroke is attained. It will further be evident that by the provision of the improved drill structure disclosed, the drill is not only rendered extremely compact, but also is relatively simple in design. It will also be evident that by the provision of the improved pressure fluid motor extremely powerful hammer blows are transmitted to the drill steel. Not only is a relatively powerful rotation mechanism for the drill steel attained, but also relatively large wearing surfaces for the rotating parts are provided. By the provision of the coating front annular piston portion and reduced bore in advance of the cylinder bore, improved cushioning of the piston is attained. Other advantages of the invention will be clearly apparent to those skilled in the art.

While there are in this application specifically described several forms and modifications which the invention may assume in practice, it will be understood that these forms and modifications of the same are shown for purposes of illustration and that the invention may be further modified and embodied in various other forms without departing from its spirit or the scope of the appended claims.

What we claim as new and desire to secure by Letters Patent is:

1. In a percussive tool, a cylinder having a bore, a hammer piston reciprocable in said bore and having pressure areas at its opposite extremities adapted to be subjected to the action of live pressure fluid, fluid distribution means for controlling the distribution of motive fluid with respect to said cylinder bore for effecting reciprocation of said piston, said piston having an impact surface located rearwardly of its forward extremity and adapted to strike against an element to be percussively actuated, and means for cushioning said piston only after the latter assumes its position wherein it normally delivers a blow to the percussively actuated element, said piston-cushioning means including a bore at the forward end of said cylinder and to which bore pressure fluid is supplied, said forwardly located bore being of smaller diameter than said cylinder bore and receiving the forward end of said piston whereby fluid is trapped in said forwardly located bore in advance of the piston after the blow is struck.

2. In a percussive tool, a cylinder having a bore, a piston reciprocable in said bore, fluid dis-

tribution means for controlling the distribution of motive fluid with respect to said cylinder for effecting reciprocation of said piston, said piston having its forward end of reduced diameter and having a central recess opening through its forward end surface, and the bottom wall of said recess providing an impact surface adapted to engage an element to be percussively actuated, a rotatable chuck in advance of said cylinder bore adapted to support the percussively actuated element in position to be struck by said piston, said rotatable chuck having a portion thereof extended rearwardly to such an extent that said recessed piston telescopes thereover only as said piston approaches its forward limit of travel, and means providing a chamber surrounding said chuck for receiving the forward portion of said piston, the exterior surfaces of said piston portion and said chuck respectively having, when said piston portion is received in said chamber, fluid tight fits with the walls of said chamber and said piston recess to provide a cushion for the piston.

3. In a percussive tool, a cylinder having a bore, a hammer piston reciprocable in said bore, fluid distribution means for controlling the distribution of motive fluid with respect to said cylinder bore for effecting reciprocation of said piston, said piston having a forward portion of reduced diameter and having a central recess opening through its forward end surface whereby said forward portion is annular in form, and the bottom wall of said recess providing an impact surface adapted to engage an element to be percussively actuated, a chuck adapted to support the percussively actuated element in position to be struck by said piston, said chuck having a portion thereof extended rearwardly to such an extent and of such external diameter that said recessed piston telescopes thereover with a fluid tight fit only as the piston approaches its forward limit of travel, and means providing a wall surrounding said chuck in spaced relation to the latter and cooperating with the latter to provide an annular chamber for receiving the forward portion of said piston, said fluid distribution means adapted to supply pressure fluid to said chamber prior to the entry into said chamber of said forward portion, the radial dimension of said annular chamber and the radial dimension of said annular forward portion of said piston being substantially the same whereby the inner and outer walls of said forward portion of said piston are sealing fits for said chuck and said second mentioned wall respectively, the rearward portion of said second mentioned wall so related to the path of piston travel and said impact surface so related to the forward end of the piston that said forward end enters said annular space only after the piston reaches the position in its forward travel in which impact on a percussively actuated element normally takes place.

4. In a percussive tool, a cylinder having a bore, a hammer piston reciprocable in said bore and having a central recess opening through an end surface thereof and also having an impact surface adapted to strike blows on an element to be percussively actuated, a head for said cylinder bore having a portion projecting axially into said cylinder bore in spaced relation to the circumferential wall of the latter and receivable in said piston recess when said piston approaches its limit of travel in one direction, said piston having the wall thereof bounding said central recess cylindrical at at least a portion thereof

and of an internal diameter substantially the same as the external diameter of said projecting cylinder head portion whereby when said recess and projecting portion are in longitudinally overlapping relation the portion of said cylinder bore surrounding said projection and the space within said central recess have communication cut off between them, fluid distribution means including means for supplying motive fluid to said portion of said cylinder bore when such communication is cut off, the length of said projecting portion with respect to the stroke of the piston being such that said piston moves off of said projecting portion prior to the reaching of the limit of its opposite stroke.

5. In a percussive tool, a cylinder having a bore, a generally cylindrical piston reciprocable in said bore and adapted to deliver impact blows to a working implement, said piston being of substantially the same external dimensions throughout its length and having opposed pressure areas at its opposite ends, mechanism operated by said piston for intermittently rotating the working implement including rotation flutes extending longitudinally of the exterior surface of said piston between its opposite extremities, a chuck mechanism for the working implement including a rotatable annular chuck nut disposed coaxial with said cylinder and surrounding said piston at portions of its greatest external dimensions, said chuck nut having straight keys engaging said rotation flutes in all positions of said piston, said chuck nut being disposed wholly in advance of the rear end of said piston when the latter is in its forward position, and a rotatable sleeve to which said chuck nut is secured and having a bore in advance of said chuck nut and of the same diameter as said cylinder bore for receiving the forward portion of said piston, and fluid distribution means for supplying motive fluid to the remote ends of said bores to act on said piston-pressure-areas to effect reciprocation of said piston.

6. In a percussive tool, a cylinder having a bore, a hammer piston reciprocable in said cylinder bore and of the same external diameter at most points throughout its length and having a forwardly facing impact surface adapted to strike against an element to be percussively actuated, fluid distributing means for distributing motive fluid with respect to the opposite ends of said cylinder bore for effecting reciprocation of said piston, means providing a bore located in advance of said cylinder bore in alignment therewith and adapted to receive the forward end portion of said piston as the latter approaches its forward limit of travel, and means for supplying live pressure fluid from the front end of said cylinder bore to said last mentioned bore to act on the forward end portion of the piston to move the latter rearwardly including passages extending longitudinally along the exterior surface of said piston between said cylinder bore and said forwardly located bore, said passages at their forward ends terminating rearwardly of said forward end portion of said piston so that when said end portion is received in said forwardly located bore said passages are cut off from said last mentioned bore.

7. In a percussive tool, a member providing a longitudinal bore and a communicating reduced front bore, the latter having concentric inner and outer walls and closed at its forward end, a hammer piston reciprocable in said longitudinal bore and having an impact surface adapted to

strike against an element to be percussively actuated, fluid distribution means for distributing pressure fluid with respect to said bores to effect movement of said piston, said piston also having a reduced front end portion of annular cross section receivable in said reduced front bore in fluid tight engagement with the concentric walls thereof, but only after the piston assumes its position wherein it normally delivers a blow to the percussively actuated element, thereby to trap fluid in said reduced bore in advance of said piston to cushion the forward piston movement after the blow is struck.

8. In a percussive tool, a rotatable member providing a longitudinal bore and a reduced front bore, the latter having concentric inner and outer walls and closed at its forward end, a hammer piston reciprocable in said longitudinal bore and having an impact surface adapted to strike against an element to be percussively actuated, fluid distribution means for distributing pressure fluid with respect to said bores to effect movement of said piston, means providing a sliding interlocking connection between said rotatable member and the exterior of said piston, said piston having a reduced front end portion of annular cross section in advance of said interlocking connection and receivable in said reduced bore in fluid tight engagement with the concentric walls thereof after, but only after, said piston assumes its position wherein it normally delivers a blow to the percussively actuated element, thereby a trap fluid in said reduced bore in advance of said piston to cushion forward piston movement after the blow is struck.

9. In a percussive tool, a rotatable member provided with a bore the forward portion of which has concentric inner and outer walls and is closed at its forward end, a hammer piston reciprocable in said bore and having an impact surface adapted to strike against an element to be percussively actuated, fluid distribution means for distributing pressure fluid with respect to said bore to effect movement of said piston, said piston having sliding interlocking connection with said rotatable member, said piston having its forward portion in advance of said connection of annular cross section and movable in fluid tight engagement with said concentric walls after, but only after, said piston assumes its position wherein it normally delivers a blow to the percussively actuated element, thereby to trap fluid in the forward end of said bore in advance of said piston to cushion the forward piston movement after the blow has struck.

Certificate of Correction

Patent No. 2,461,527

February 15, 1949

JOHN C. CURTIS ET AL.

It is hereby certified that error appears in the printed specification of the above numbered patent requiring correction as follows:

Column 10, line 33, for the words "a trap" read *to trap*;
and that the said Letters Patent should be read with this correction therein that the same may conform to the record of the case in the Patent Office.

Signed and sealed this 27th day of December, A. D. 1949.

[~~initials~~]

THOMAS F. MURPHY,
Assistant Commissioner of Patents.
